Filed July 5, 1968, Ser. No. 12,631

Term of patent 14 years

Int. Cl. D21—03; D8—02

U.S. Cl. D34—5

FIGURE 1 is a front elevational view of the bowling ball pusher device showing my new design;

FIGURE 2 is a plan view thereof;

FIGURE 3 is a side elevational view thereof taken along irregular section line 3—3 of FIGURE 1.

The dominant feature of my design resides in the portion shown in full lines with fragmentary showings in FIGS. 2 and 3 for convenience of illustration.

I claim:

The ornamental design for a bowling ball pusher device, substantially as shown and described.
